(57) **CLAIM**

The ornamental design for a children's climbing triangle set as shown and described.

DESCRIPTION

FIG. 1 is a front, top and right perspective view of a children's climbing triangle set showing my new design; FIG. 2 is a front elevation view thereof, a rear elevation view thereof being a mirror image of the front elevation view; FIG. 3 is a top plan view thereof;

FIG. 4 is a bottom plan view thereof;

FIG. 5 is a right elevation view thereof;

FIG. 6 is a left elevation view thereof;

FIG. 7 is a front, bottom and left perspective view thereof; FIG. 8 is a perspective view of a middle element of the children's climbing triangle set, shown separately for completeness of illustration thereof;

FIG. 9 is a perspective view of a right element of the children's climbing triangle set, shown separately for completeness of illustration thereof; and,

FIG. 10 is a perspective view of a left element of the children's climbing triangle set, shown separately for completeness of illustration.

The broken lines depict portions of the children's climbing triangle set that form no part of the claimed design.

1 Claim, 10 Drawing Sheets
